UNITED STATES PATENT OFFICE

HUGH G. BUCHAN, OF PHILADELPHIA, PENNSYLVANIA

MECHANISM FOR SHIFTING SHEETS

Application filed November 18, 1931. Serial No. 575,723.

This invention relates to a mechanism and method for shifting loose sheets.

At the present time, it has been the common practice to keep visible index records in 5 Tengwell binders which have a set of curved prongs upon each cover member. In view of the fact that the record sheets often become obsolete, they have to be removed from the binder. More or less difficulty has heretofore existed in the removal of such obsolete sheets. It was necessary to open the 10 binder at the right spot and then shift the sheets in front of the obsolete sheet to the adjacent side of the binder which then had 15 to be opened so that the obsolete sheet could be removed. It will be appreciated that where many obsolete sheets occur, this involves a great deal of painstaking effort.

According to this invention, it is proposed 20 to use straight impaling posts upon one binder cover with a holding and compression strip having straight prongs positioned over the top of the record sheets and to use a curved prong shifter for separating the 25 sheets when it is desired to remove the obsolete sheets.

The invention comprises the novel method and combination of parts hereinafter described and more particularly pointed out 30 and defined in the appended claims.

In the accompanying drawings which illustrate a preferred form of this invention and in which similar reference numerals refer to similar features in the different views: 35 Figure 1 is an interior plan view of a straight prong expandable binder adapted for retaining overlapping visible index sheets.

Figure 2 is a view similar to Figure 1 illustrating the shifter mechanism in place. 40 Figure 3 is a view similar to Figure 2 illustrating the method of shifting the sheets.

Figure 4 is a view similar to Figure 3 but illustrating the prongs on the sheet shifter lying over to the left so that obsolete sheets 45 may be removed from the binder.

Figure 5 is an enlarged sectional view taken substantially on the line V—V of Figure 2 looking in the direction of the arrows and illustrating in dotted lines the prongs as they are swung over when it is desired 50 to remove obsolete sheets.

Figure 6 is an enlarged sectional view taken on the line VI—VI of Figure 2.

Figure 7 is an enlarged fragmentary sectional view taken upon the line VII—VII of 55 Figure 6.

Figure 8 is a perspective view of the sheet shifter.

In accordance with this invention, there is illustrated an expandable binder consisting of 60 two sections. One section embodies an angular back member 1 which slidably cooperates with an angular back member 2 of the other section. Suitable telescoping guide posts 4 at the ends of the back members serve 65 to guide the same in their expanding and contracting movements. The usual cover members 3 are hinged to the upper edges of the angular back members 1 and 2 as is usual in the art. The angular back section 1 supports a plurality of straight impaling posts 5 as shown in Figures 5 and 6 for retaining 70 overlapping visible index sheets 6. A compression strip 7 (Figure 1) provided with straight impaling posts 8 is adapted to be applied to the top of the sheets for maintaining 75 the sheets in position in the binder and preventing their escape from the impaling posts 5.

When it is desired to remove obsolete records, the binder is opened as shown in Figure 1 and the upper compression strip 7 is removed from the top of the sheets and is laid aside. The sheet shifter involving this 80 invention is then inserted in the back of the binder as illustrated in Figure 2. The shifter which is clearly shown in Figure 8 consists of a base portion 9 having an upwardly and inwardly inclined flange 10 along one longitudinal edge and having an angular 85 90

rest 11 extending along the opposite margin. A post plate 12 is hinged to the base 9 and carries a plurality of curved prongs 13. Upon the end of the base, there are retaining 5 clips 14. When this sheet shifter is positioned in the back portion of the binder as shown in Figure 2, the clips 14 will take over the guide posts 4 and the angular rest 11 will engage over the lower edge or border of the 10 cover member 3 as shown in Figure 5. With reference to Figure 2, it will be noted that the prongs 13 are so spaced that they register with apertures in the record sheets.

After the sheet shifter has been inserted 15 in the binder, the record sheets 6 may be transferred thereon by simply lifting the same and swinging the same over to the left hand cover member. As these sheets are swung over, they will automatically engage the prongs 20 13 on the shifter and retain their proper positions. The operator will continue to manually transfer the sheets to the shifter as shown in Figure 3 until an obsolete sheet is encountered. Assuming that the sheet 6a as 25 shown in Figures 3 and 4 is an obsolete sheet which it is desired to remove, the operator will swing the impaling prongs 13 to the left as shown in Figure 4 so that the sheet 6a may be readily removed. Thereafter the prongs 30 13 may be swung back into their shifting positions and the operator will continue to transfer the sheets thereon until another obsolete sheet is encountered when the operation of removing the sheet may be repeated. 35 When the obsolete sheets have been removed from the binder, the sheets on the left hand cover may be swung over upon the prongs 13 to the right hand cover where they will immediately engage the proper impaling posts 40 and maintain their proper relative positions.

From the foregoing, it will be apparent that a novel method has been devised for removing obsolete sheets from a visible index binder whereby the relative positions of the 45 sheets are always maintained without any special care or effort. It will be further appreciated that the novel form of sheet shifter which provides this novel operation may be used in connection with any number of binders of proper design one after the other. It 50 will also be appreciated that the difficult and tedious operation heretofore required in connection with the Tengwell binders is avoided.

55 I am aware that many changes may be made and numerous details of construction may be varied through a wide range without departing from the principles of this invention, and I therefore do not purpose limiting 60 the patent granted hereon otherwise than necessitated by the appended claims.

I claim as my invention:

65 1. A sheet shifter for use in a binder having guide posts comprising a base portion having downwardly projecting resilient clips

for engaging said guide posts, a strip hinged to said base and hook-like prongs attached to said strip.

2. A sheet shifter for use in an expandible binder having telescopic guide posts, a base member adapted to fit in said binder and rest upon said guide posts, said base member having means engaging said guide posts, a strip hinged to said base member, and hook-like prongs upon said strip. 70

3. A sheet shifter comprising a base portion having an angular member extending along one edge, and having downwardly extending stop members, a strip hinged to said base portion and curved prongs on said strip. 80

In testimony whereof I have hereunto subscribed my name at Philadelphia, Philadelphia County, Pennsylvania.

HUGH G. BUCHAN.
